UNITED STATES PATENT OFFICE.

SAMUEL H. BOYLAN, OF JOPLIN, MISSOURI.

SLIME CONCENTRATOR.

Application filed September 23, 1922. Serial No. 590,105.

To all whom it may concern:

Be it known that I, SAMUEL H. BOYLAN, a citizen of the United States, residing at Joplin, in the county of Jasper and State of Missouri, have invented certain new and useful Improvements in Slime Concentrators, of which the following is a specification.

This invention relates to what is termed slime concentrators and is employed for treating mixtures of exceedingly fine sand and ore with an excess of water to settle the heavier solids and reduce the volume of water preparatory to the final dressing of the ore for market.

In the present invention, I provide a pivoted table having a plurality of decks provided with upper surfaces of fabric or rough surfaced material, the decks and table being normally arranged at an inclination to permit slow movement of feed over each deck whereby the ores contained therein will be deposited on the surface of the decks. I further provide means to periodically swing the table to permit a rapid flow of water over the decks to remove the deposited material.

An object of the invention is the provision of means for automatically tipping the table at desired intervals.

A further object is the provision of a pair of discharge outlets communicating with the table in either of its two positions to carry off the normal discharge through one outlet and the deposited material through a second outlet.

A further object is the provision of an apparatus of this type which is efficient in operation, simple in construction, and of great durability.

In the accompanying drawings, I have shown one embodiment of my invention. In this showing:

Figure 1 is a side elevation showing a table in normal position, and showing, in dotted lines, the position of the table when tipped,

Figure 2 is a transverse vertical sectional view on line 2—2 of Figure 1,

Figure 3 is a central vertical longitudinal sectional view,

Figure 4 is a transverse vertical sectional view on line 4—4 of Figure 1,

Figure 5 is an end elevation,

Figure 6 is a plan view of the inlet end of the table,

Figure 7 is a detail view of a portion of the control mechanism,

Figure 8 is a similar view of a control member arranged at the inlet end of each deck, and,

Figure 9 is a detail view of a discharge valve forming a portion of the control mechanism.

Referring to the drawings, the reference numeral 1 designates a suitable base or foundation having longitudinal supporting beams 2 arranged thereon. A table 7 is pivotally supported on vertical posts 3, the inlet end normally resting on stops 19 attached to vertical posts 4. The upper ends of these posts are connected by suitable bars 5. The posts 3 and 4 are arranged on each side of the table, and each pair of the posts are connected adjacent their upper ends by transverse members 6. The table is substantially box-shaped and provided with bearing member 8 on its lower surface. This bearing member is adapted to receive a shaft 9, rotatably mounted in suitable openings in the posts 3. The table is provided with partial side walls 10, and within these walls are provided trays 11 forming the decks. A plurality of decks may be employed, the decks being suitably spaced from each other and arranged substantially parallel to the bottom of the table. Each of the decks is provided with a suitable covering 12 of fabric or other rough surfaced material, retained in position by longitudinal strips 13. The ends of the decks adjacent the inlet are provided with extensions 14, arranged in stepped relation as shown, and suitable end walls 15 are arranged at the outer ends of each of the extensions. A transverse member 16 is arranged at the inlet of each deck, and these transverse members are provided with a plurality of openings 17 for the passage of the feed for the deck. By reference to Figure 3 of the drawings, it will be seen that the extensions 14 and the vertical members 15 and 16 form troughs 18 for distributing the feed on the decks.

The feed is delivered from a supply source to a receiver 20, arranged at the top of the vertical supports and this receiver is provided with an outlet 21, communicating with a flexible tube 22. The end of this flexible tube communicates with a transverse pipe 22' arranged at the inlet end of the table and supported on longitudinal

members 23, secured to the side walls of the table. The transverse pipe 22' is closed at one end and communicates with a longitudinal pipe 24, arranged substantially centrally of the table and inclined to pass over the troughs 18. A header 25 is arranged over each trough and is provided with suitable openings 26, controlled by any desired type of valve and adapted to discharge into the respective troughs.

The outlet end of the table is provided with an offset lower wall 27 which inclines toward the center, as shown, (see Figure 2) and has an outlet opening 28. The decks 11 terminate inwardly of the end wall 29, forming a space 30 above the inclined lower wall to permit free flow of the material to the outlet opening. When the apparatus is in normal position, the waste material passes through the outlet opening 28 to a trough 31, whence it is conveyed to a waste launder.

The apparatus for periodically tipping the table consists of a receptacle 32, arranged beneath the table adjacent the outlet end and secured thereto. This receptacle is provided with an inlet opening 33, arranged on one side and is adapted to be connected to a reservoir 34, arranged at a suitable elevation by a flexible tube 35. As shown, a control valve 36 is arranged at the outlet of the reservoir. The receptacle 32 is provided with an outlet pipe 37, disposed on the opposite side to the inlet opening and communicating with a valve casing 38, shown in Figure 9 of the drawings. The valve casing is provided with a valve seat 39, adapted to receive a valve 40, normally retained in closed position by a spring 41. The valve is provided with a stem 42, projecting through the valve casing and connected to a pivoted lever 43. This lever is pivoted in a suitable bracket 44, arranged on the valve casing and is provided with an offset lower end 45. A discharge pipe 46 is arranged beneath the valve, and is provided with a projection 47, adapted to engage the valve stem when the table is in lowered position, to open the valve and permit discharge of liquid from the receptacle 32. A chute 48 is arranged adjacent the outlet end of the table beneath the chute 31 and is adapted to communicate with the outlet opening 28 when the table is in lowered position (see Figure 1). As shown, the chute is provided with side walls 49, having an inner edge 50, curved on a radius from the center of shaft 9 so that the end of the outlet 28 will properly pass over the wall of the chute when the table is raised and lowered.

At the inlet end of the machine, there is provided an apparatus to cushion the table when striking the stop when it swings in either direction. This apparatus as shown, consists of an air cylinder 51 having a flange 52 at the bottom with apertures therethrough

for bolts to securely attach same to a suitable support. A piston head 52 is fitted in the cylinder and is provided with a piston rod 53 extending through the top of said cylinder a considerable distance. A collar 54 is securely attached to said piston rod near its upper end. This collar is provided with apertures for the reception of flexible cables 55, the other end of each of said cables being attached to the bottom of the table 7 as shown. Two small air cocks 56 are mounted in said cylinder and communicate with the air chamber to regulate the ingress and egress of the air to and from the cylinder. As shown, one of the cocks is arranged adjacent the top of the cylinder, and the other adjacent the bottom. A block 57 is attached to the lower side of the table 7 to contact with the upper end of the piston rod during the return of the table to normal position when in operation.

In operation, the slime is constantly fed to the decks from the reservoir 20 through the flexible tube 22, thence through pipe 22', pipe 24, and headers 25 to the troughs 18. From the troughs 18, the material passes through the openings 17 in the transverse members 16 to the decks. When the table is in its normal position, there is a very slight incline from the inlet end of the table to the outlet end, and the slime flows over the decks very slowly, depositing the fine ores and solids contained therein on the fabric 12. The weight of the parts on each side of the shaft 9 is distributed to normally retain the deck in its operative position when the reservoir 32 is empty. The reservoir 32 is of such size that the weight of a body of water sufficient to fill it is also sufficient to overbalance the table and water flowing from the reservoir 34 through the flexible tube 35 fills the lower reservoir 32 at desired intervals and tips the table. The rate of flow of water to the reservoir 32 may be controlled by valve 36 and thus the tipping intervals may be regulated at will.

In normal operation, the material passing from the decks enters the space 30 and then flows through the outlet 28 to the chute 31 which conveys it to the waste launder. When the reservoir 32 fills with water and the table is tipped, the outlet 28 communicates with the trough or chute 48, which conveys the deposited material to a desired point. When the table is in the tipped position, as shown in dotted lines in Figure 1 of the drawings, the rate of flow is materially increased, and the deposited ores are washed from the fabric surface of the decks into the chute 48.

As the table lowers, the valve 40 is opened by the contact of the valve lever 43 and projection 47, discharging the contents of receptacle 32 into the pipe 46. This removes the additional weight from the out-

let end of the table and the table returns to normal position. As the inlet end of the table lowers, it contacts with the stops 19 which retain it in its proper position.

When the table is in normal position, the 5 piston 52 is depressed to its lowest position and the cables 55 are slack, but when the table periodically tips forward, the inlet end is raised unimpeded until about one-half its 10 elevation is attained when the cables become taut and the piston is drawn upwardly against the air in the upper part of the cylinder which is gradually forced out through the air cock preventing any violent 15 shock or movement of the table while discharging its load; when the return movement of the table is begun, it is unimpeded until about one-half the descent of the inlet end is attained when the block 57 on the 20 under side of the table 7 contacts with the upper end of the piston rod 53, forcing it downwardly against the air in the lower end of the cylinder. The air is gradually forced through the lower air cock. The passage of 25 the air through the air cocks may be regulated at will so that there is no perceptible jar in the movement of the table.

It is to be understood that the form of my invention herewith shown and described is to be taken as a preferred example of 30 the same, and that various changes in the shape, size, and arrangement of parts may be resorted to without departing from the spirit of the invention or the scope of the subjoined claims.

Having thus described my invention, I 35 claim:

1. In a device of the character described, a pivotally mounted table, a plurality of decks mounted on said table substantially 40 parallel to each other, said decks being provided with fabric surfaces, said table being provided with an inlet and an outlet for the introduction and discharge of material to be concentrated and being normally inclined 45 downwardly toward said outlet, a pair of discharge members arranged adjacent said outlet end of the table, one of said discharge members being arranged above the other,

said upper discharge member forming a substantial continuation of said outlet and normally communicating therewith, and means for tipping said table at intervals to bring the outlet end into communication with said lower discharge member. 50

2. In a device of the character described, a pivotally unitary mounted table, a plurality of decks arranged on said table, inlet troughs arranged at one end of said decks, a header rigidly carried by said table and adapted to feed material to said troughs, transverse members arranged between said decks and said troughs adjacent said troughs, said members being provided with a plurality of openings, and means for tipping said table at intervals. 60

3. In a device of the character described, a pivotally mounted table, a plurality of decks mounted on said table in spaced relation, each of said decks being arranged inwardly of the next lower decks at the inlet end of the trough, forming a plurality of stepped inlet chambers, a header communicating with each of said chambers, the outlet end of said table being provided with 70 a lowered discharge opening, and means for tipping said table at intervals. 75

4. In a device of the character described, a pivotally mounted unitary table divided horizontally to form a plurality of spaced 80 decks, inlet troughs arranged at one end of said decks, a header adapted to feed material to said troughs, transverse members arranged between said decks and said troughs, said members being provided with 85 a plurality of openings, means for tipping said table to a predetermined inclination at predetermined intervals, and means for lessening the speed of said table as it reaches the limits of the downward and upward 90 movements.

In testimony whereof, I affix my signature in presence of two witnesses.

SAMUEL H. BOYLAN.
